Attorney,

UNITED STATES PATENT OFFICE.

WALTER C. BECKWITH, OF FOSTORIA, OHIO, ASSIGNOR TO THE BEVINGTON SIGNAL COMPANY, OF SAME PLACE.

DESIGN FOR A LANTERN-BODY.

SPECIFICATION forming part of Design No. 18,717, dated November 6, 1888.

Application filed August 1, 1888. Serial No. 281,696. Term of patent 3½ years.

To all whom it may concern:

Be it known that I, WALTER C. BECKWITH, a citizen of the United States, and a resident of the town of Fostoria, in the county of Seneca and State of Ohio, have invented a certain new and useful Design for a Lantern-Body, of which the following is a specification.

The design is particularly applicable to lanterns for campaign purposes, it being somewhat characteristic of one of the political parties now in the field.

In the accompanying drawing the figure shows a lantern embodying my design.

The outline of the lantern globe or body is substantially an ogee curve, as shown, and the body is marked by transverse bands *a a* at top and bottom and smaller bands, *b b*, between them, with a clear interspace, *c*, intervening between each band *b* and the adjacent band *a*. Between the bands *b* is a rather broad space or zone, *d*, which is decorated by dots or spots

e, these latter being gathered into groups, as shown.

The colors employed impart a bright and pleasing effect to the lantern. The lanterns 25 ornamented as herein described are very attractive and form objects of beauty, valuable aside from their use for campaign purposes.

What I claim as new, and desire to secure by Letters Patent, is—

The design for lanterns herein described and shown, consisting of the body portion, the outline of which is substantially an ogee curve and ornamented by the upper and lower bands separated by a zone, upon which are represented groups of dots, substantially as set forth.

W. C. BECKWITH.
